UNITED STATES PATENT OFFICE.

CHARLES E. RILEY, OF NEWTON, MASSACHUSETTS, ASSIGNOR TO HOWARD & BULLOUGH AMERICAN MACHINE CO., LIMITED, OF PAWTUCKET, RHODE ISLAND.

TRAVELER-CLEARER FOR RING-SPINNING FRAMES.

SPECIFICATION forming part of Letters Patent No. 789,455, dated May 9, 1905.

Application filed September 19, 1904. Serial No. 224,939.

To all whom it may concern:

Be it known that I, CHARLES E. RILEY, a citizen of the United States, residing at Newton, in the county of Middlesex and State of Massachusetts, have invented a new and useful Improvement in Traveler-Clearers for Ring-Spinning Frames, of which the following is a specification.

This invention has reference to an improvement in traveler-clearers for ring-spinning frames, and more particularly to an improvement in the means for securing the wire clearer to the spinning-frame in its operative position.

15 In the use of traveler-clearers as heretofore constructed it has been found difficult to properly secure them either to the ring-holder or ring-rail without making two or more bends in the wire clearer, thus weakening and 20 shortening the life of the clearer and increasing the cost of the same.

The object of my invention is to secure a semicircular wire clearer with only one bend to a ring-holder without removing the ring 25 from the holder.

A further object of my invention is to simplify the construction of the wire clearer and the means for holding the clearer in the ring-holder, thereby lessening the cost of the same.

30 My invention consists in the peculiar and novel construction of a semicircular wire traveler-clearer and the means for holding the clearer in the ring-holder, said means consisting of a circular groove in the bottom of 35 the ring-holder-supporting flange, the usual slot in the ring-holder, and the top of the ring-rail, and a set-screw in screw-thread engagement with the ring-rail and bearing on the ring-holder, as will be more fully set forth 40 hereinafter.

Figure 1 is a top plan view of part of a ring-rail, showing my improved traveler-clearer and ring-holder secured to the ring-rail. Fig. 2 is a bottom plan view of the ring-holder and traveler-clearer removed from the ring-rail. Fig. 3 is a transverse sectional view taken centrally through the ring-rail, ring-holder, traveler-clearer, and ring, showing the means for

securing the clearer to the ring-holder and the ring-holder to the ring-rail; and Fig. 4 is 50 a perspective view of my improved semicircular wire traveler-clearer.

In the drawings, *a* indicates the ring-rail of a spinning-frame; *b*, the ring-holder; *c*, the semicircular wire traveler-clearer; *d*, the ring, 55 and *e* the traveler. The ring-rail *a* has the usual circular hole *a'* and the set-screw *a''*, which extends through the ring-rail from its outer edge to the hole *a'*, as shown in Fig. 2. The ring *b* extends downwardly in the hole *a'*, in which it is secured by the set-screw *a''*, and has the outwardly-extending circular flange *b'*, in the bottom of which is the circular groove *b''*, the circular recess *b'''* in the top of the ring *d*, and the usual slot *b'*, by which 65 the ring-holder is sprung outward to receive the ring. The wire traveler-clearer *c* has the semicircular portion *c'*, shaped to fit in the groove *b''*, and the upwardly-bent end *c''*, adapted to extend upward through the slot *b'* in the 70 ring-holder, as shown in Fig. 3.

By the novel construction of the groove *b''* in the bottom of the flange *b'* of the ring-holder *b* the semicircular portion *c'* of the wire clearer *c* is firmly held in the groove *b''* between the bottom of the groove and the top of the ring-rail *a*, as shown in Fig. 3, and can be easily removed or replaced by loosening the set-screw *a''* and removing the ring-holder *b* from the ring-rail *a*. The circumference of the 80 groove *b''* being greater than the circumference of the ring *d* brings the upwardly-bent end *c''* of the clearer *c* through the slot *b'* in the ring-holder in its correct operative position in relation to the traveler *e* with the use of 85 only one bend in the clearer, as shown in Fig. 4.

By the use of my improved traveler-clearer and means for holding the same the clearer is easily and firmly secured in its correct position to remove the fiber from the traveler 90 with only one bend in the clearer and without removing the ring from the ring-holder, and a better result is attained as a whole than has heretofore been done.

It is evident that the groove *b''* in the bottom of the flange *b'* could be dispensed with,

if desired, and a similar groove formed in the top of the ring-rail a to hold the semicircular portion c' of the clearer c without materially affecting the spirit of my invention.

5 Having thus described my invention, I claim as new and desire to secure by Letters Patent—

1. In a traveler-clearer for ring-spinning frames, the combination of a ring-rail, a semicircular wire clearer having an upwardly-bent 10 end, and a ring-holder having an outwardly-extending circular flange in the bottom of which is a circular groove, as described.

2. In a traveler-clearer for ring-spinning frames, the combination of a ring-rail in which 15 are circular holes, a ring-holder having a slot, an outwardly-extending circular flange in the bottom of which is a circular groove, and a circular recess in the top adapted to hold a spinning-ring by clamping, a semicircular

wire traveler-clearer having an upwardly-bent 20 end, and means for securing the ring-holder in the ring-rail, as described.

3. In a traveler-clearer for ring-spinning frames, the combination of the ring-rail a in which is the circular hole a' and the set-screw 25 a^2 , the ring-holder b having the flange b' in the bottom of which is the groove b^2 , the recess b^3 for the ring d and the slot b^4 , and the wire traveler-clearer c having the semicircular portion c' and the upwardly-bent end c^2 , 30 all as shown and for the purpose as described.

In testimony whereof I have signed my name to this specification in the presence of two subscribing witnesses.

CHARLES E. RILEY.
